DESIGN FOR A DRESS

Lucy Hoshafian, New York, N. Y.

Application July 12, 1941, Serial No. 102,082

Term of patent 3½ years

To all whom it may concern:

Be it known that I, Lucy Hoshafian, a citizen of the United States of America, residing in New York city, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination or the specific dress disclosed of the specific pockets in association with the stitched collar as shown.

I claim:

The ornamental design for a dress, substantially as shown and described.

LUCY HOSHAFIAN.
